UNITED STATES PATENT OFFICE.

WILLIAM C. DULL, OF TAFT, CALIFORNIA.

PUMP-JACK BEARING.

Application filed June 27, 1923. Serial No. 648,035.

To all whom it may concern:

Be it known that I, WILLIAM C. DULL, a citizen of the United States, residing at Taft, in the county of Kern, State of California, have invented certain new and useful Improvements in Pump-Jack Bearings; and I do hereby declare the following to be a full, clear, and exact description of the invention, such as will enable others skilled 10 in the art to which appertains to make and use the same.

This invention relates to new and useful improvements in pumping jacks, and particularly to bearings therefor.

One object of the invention is to provide a bearing for a jack of this character which is capable of adjustment longitudinally and transversely of the base, so that the accurate vertical position of the pump 20 rod may be accomplished.

Another object is to provide an adjustable bearing of this character which can be easily and quickly adjusted without disconnecting the jack from the pump rod.

Other objects and advantages will be apparent from the following description when taken in connection with the accompanying drawing.

In the drawing:

Figure 1 is a top plan view of a pump jack bearing made in accordance with the present invention.

Figure 2 is a vertical transverse central sectional view on the line 2—2 of Figure 1.

Figure 3 is a vertical longitudinal central sectional view on the line 3—3 of Figure 1.

Referring particularly to the accompanying drawing, 10 represents a base plate which is secured to a foundation 11 by means of the bolts or screws 12. On the upper face of the plate 10 is a longitudinal flange 13, extending the entire length of the base plate, and the transverse flanges 13', connected with the ends of the flange 13, and extending across the upper face of the plate, at the ends thereof. Disposed on the upper face of the plate 10, and loosely enclosed by the said flanges, is a bearing block 14, said block being of such dimensions as to be permitted to move longitudinally and transversely of the base plate. Formed longitudinally in the upper face of the bearing block, and terminating short of the ends thereof, is a transversely concave channel or groove 15, in which is seated the correspond-

ingly shaped bearing shaft 16 of the triangular pump jack 17. This jack includes the vertical arm 18 and the horizontal arm 19, the former having a cable or rod 20 connected to its outer end, for connection with the main driving wheel, not shown, while the outer end of the arm 19 is connected to the upper end of the pump rod 21, which is disposed within the well 22. 60 As is usual, in this type of pumping device, the cable or rod 20, by its reciprocations, will cause the triangular jack to rock within the channel 15, of the bearing block 14, with the result that the outer end of the arm 19 reciprocates the pump rod to perform the act of pumping the liquid from the well. The longer side walls of the channel 15 are beveled or inclined upwardly and outwardly, as shown at 23, to permit 70 the proper rocking movement of the jack. These beveled faces 23 are not, however, as long as the channel, as clearly seen in Figures 1 and 3, and the upper edges of said faces are beveled downwardly and outwardly, as at 24, so that the horizontal arm 19, of the jack, may properly swing on its pivot. 75

The intermediate portion of the longer flange 13 is downwardly and outwardly inclined for a distance approximately the length of the bevel 24, said bevel, as shown at 25, being in the same plane, or approximately the same plane as the bevel 24. 80

In the longer flange 13, adjacent each end of the bevel face 25, is an adjusting bolt or screw 26, the inner end of which bears against the adjacent vertical side face of the bearing block 14, while similar bolts or screws 27 are disposed through the transverse flanges 13' and have their inner ends bearing against the vertical end faces of the block 14. Lock nuts 28 are disposed on the bolts or screws for maintaining them in their adjusted positions. 90

It will thus be seen that, when the pump rod 21 is out of vertical alignment, transversely of the well, in the direction longitudinally of the base plate, the screws 27 are turned to move the block 14 longitudinally in the proper direction, on the base plate 10. Should the jack be so positioned that the outer end of its arm 19 is too far out or too far in, the screws 26 are turned to move the block 14 in the proper direction to bring the outer end of the arm 19 directly above the center of the well. 100 105 110

From the foregoing it will readily be seen that the proper adjustment of the jack, with respect to the well, and pump rod, may be accomplished without the necessity of disconnecting the jack from the pump rod, or from the operating cable or rod, with the consequent saving of considerable time, and the accompanying monetary consideration.

What is claimed is:

- 5 10 A pumping jack bearing comprising a base having upstanding flanges on the ends thereof and a longitudinal flange on one side connected with the end flanges, bolts disposed horizontally through the said

flanges, and a block disposed on the base and 15 engaged with the said bolts, said base having a longitudinal central channel with the intermediate portions of its side walls upwardly and outwardly beveled, the intermediate portion of the longitudinal flange 20 of the base being downwardly and outwardly beveled.

In testimony whereof, I affix my signature, in the presence of two witnesses:

WILLIAM C. DULL.
